UNITED STATES PATENT OFFICE

168,846

HANGER

William Lincoln and James De Muth,
Huntington Park, Calif.

Application September 2, 1952, Serial No. 21,282

Term of patent 14 years

(Cl. D14—6)

To all whom it may concern:

Be it known that we, William Lincoln and James De Muth, citizens of the United States, residing in Huntington Park, in the county of Los Angeles and State of California, have invented a new, original, and ornamental Design for a Hanger, of which the following is a specification, reference being had to the accompanying drawing, forming a part thereof.

Figure 1 is a perspective view of a hanger, showing our new design,

Figure 2 is a front elevational view thereof,

Figure 3 is a top plan view, and

Figure 4 is a bottom plan view.

We claim:

The ornamental design for a hanger, substantially as shown.

WILLIAM LINCOLN.
JAMES DE MUTH
